BY *Wm. H. Co.*
ATTORNEYS.

UNITED STATES PATENT OFFICE

JAMES R. O'NEIL, OF SAN FRANCISCO, CALIFORNIA

SMOKING SET

Application filed August 20, 1928. Serial No. 300,934.

My invention relates to improvements in smoking sets, and it consists of the combinations, constructions and arrangements hereinafter described and claimed.

An object of my invention is to provide a smoking set which will resemble a standard telephone. The article is designed for a novelty as well as for the purpose of utility. The head of the telephone is movable from inoperative to operative position, and is in reality an ash tray. The mouthpiece supports a cigar or cigarette holder, and the mouthpiece may be turned for opening the cover to the ash tray, and this turning movement, coupled with the raising of the telephone head, swings the cigarette holder into operative position.

The head when raised releases a stop member and permits the receiver hook to swing upwardly when the receiver is removed. The upward swinging of the hook closes a circuit through a cigarette lighter carried by the end of the receiver.

The front of the base removably carries a package of cigarettes.

Other objects and advantages will appear as the specification proceeds, and the novel features will be particularly pointed out in what I hereinafter claim.

My invention is illustrated in the accompanying drawings forming a part of this application, in which

Figure 1 is a section along the line 1—1 of Figure 2;

Figure 2 is a front elevation of the device, a portion being broken away;

Figure 3 is a section along the line 3—3 of Figure 1;

Figure 4 is a perspective view of a cigarette package holder;

Figure 5 is a diagrammatic view of a modified form of the device; and

Figures 6 and 7 are views showing the ash tray cover in closed and open positions.

In carrying out my invention I provide a base 1 which resembles a standard telephone base. In place of the dial used on automatic telephones, I mount a bracket 2 which is U-shaped and which has upwardly-extending legs 3. Each leg has a recess 4 of the shape

shown in Figure 1. A metal container 5 (see Figure 4) has its lower end received in the recess 4. This container is large enough to hold a package of cigarettes, and is provided with a spring 6 for yieldingly contacting with the package. Figure 5 shows how the container 5 supports a package of cigarettes 7.

The base 1 carries an upright 8, and this upright is capped by a casting 9 which in turn is bifurcated at 10 for receiving the tongue 11 of a telephone head 12. A hook 13 pivots on a rod 14 carried by the casting 9, and the tongue 11 pivots in the bifurcated end 10, which permits the head 12 to be swung into the dotted-line position shown in Figure 1.

I will first describe the switch which is housed in the upright 8 before setting forth the structure of the receiver and the mouthpiece. A bar 15 (see Figure 1) leads from the base 1 up to the pin 14. Figure 3 shows how this bar carries a spring 16 and how the latter is secured in place by a rivet 17. The spring has its free end 18 resting upon a cam edge 19 of the hook 13. A spring contact 20 is insulated from and is carried by the spring 16. This contact is yieldingly held in engagement with the contact 21 when the hook 31 is in raised position. The hook is moved into raised position when a receiver 22 (see Figure 2) is lifted therefrom. The terminal 21 is mounted upon an insulated base 23 and the latter is secured to the bar 15.

In Figure 2 I show how the receiver 22 carries a cigarette lighter 24. The wires leading from the lighter pass through a cord 25 and are connected to the terminals 20 and 21. When the head 12 is in the dotted-line position, the raising of the receiver will permit the spring 18 to close the contacts 20 and 21. This will close a circuit from a source of current (not shown) through wires 26 which lead to the switch and from the switch by the wires in the housing cord 25 to the receiver. It should be noted at this point that when the receiver 22 is upon the hook 13, the lighter 24 is disposed above the base 1. The base will therefore protect articles from touching the lighter and will obviate any tendency of a

fire being started by the heated element. Of course, as soon as the receiver is placed back upon the hook 13, the circuit is cut off to the lighter and the lighter will quickly cool.

I now come to the means for locking the hook 13 in inoperative position until the head 12 has swung into substantially vertical position. The tongue 11 has a cam edge 27, and this contacts with the top of a tubular member 28. The latter bears against the top of the hook 13 as shown in Figure 3. When the head 12 is in the dotted-line position, the spring 16 is strong enough to lift the tube 28 when the receiver 22 is removed from the hook. A swinging of the head 12 into the full-line position clamps the tube 28 down upon the hook 13 and prevents the swinging of the latter.

A stop 29 is carried by the tongue 11 and bears against a notch 30 (see Figure 1) in the casting 9 for limiting the upward movement of the head 12. The stop prevents the head from being swung into vertical position, but permits it to be moved almost into this position.

Within the head 12 I dispose an ash tray. This comprises a container 31 (see Figure 1). This container is carried by a cover plate 32. The latter has a flange 33 designed to be snugly received within the head 12. The plate 32 may be removed and carry with it the container 31. The container may then be removed from the plate and the contents emptied.

The ash tray is covered by a plate 34 which is swung into open and closed position by a handle 35 resembling the mouthpiece of a telephone. The plate 34 may have indentations 36 in its outer surface for carrying out the effect of a standard telephone. The mouthpiece 35 swivels in the plate 32 and carries a pin 37 (see Figure 6) which is pivotally connected to the plate 34. The mouthpiece is designed to be rotated through a half circle, and this rotation will swing the plate 34 into the position shown in Figure 7 so as to uncover the opening 38 into the container. The piece 34 is provided with a slot 39 that rides on a pin 40 which causes the movement shown in Figures 6 and 7.

A rotation of the mouthpiece 35 through half a circle swings a cigarette carrier 41 carried by the mouthpiece (see Figure 1) into the dotted line position and disposes this carrier in substantially a horizontal plane. In this position the carrier 41 can support a cigarette or a cigar. It also shows that the ash tray is open.

From the foregoing description of the various parts of the device, the operation thereof may be readily understood.

The imitation telephone may be placed upon a desk or other supporting surface, and the standard 8 may be grasped when it is desired to remove a cigarette from the pack-

age 7. The mouthpiece is turned and the head is swung back for permitting the hook 13 to close the circuit when the receiver is lifted therefrom. The cigarette or cigar is lighted by the cigarette lighter 34. As soon as the receiver is placed back upon the hook, the current is cut off to the light. The device is extremely novel, and at the same time has utility.

In Figure 5 I show a slightly modified form of the device. The hook 50 in this form does not close a switch but is merely a permanent and fixed part of the device. The switch is carried by a receiver 51 and is of the push button variety. The receiver 51 is grasped in the hand and the switch 52 is closed for sending a current through the cigarette lighter 24. As soon as the switch 52 is released, the current ceases to flow. Wires 53 lead from the receiver to the base 1 and then from the base to a plug 54. The purpose of leading the wires to the base is to give the device an appearance of a standard telephone. All of the other parts of the device are identical, and therefore need no further description. The same reference numerals will apply in this device that are used in the former except where changes are made.

Although I have shown and described two embodiments of my invention, it is to be understood that the same is susceptible of various changes, and I reserve the right to employ such changes as may come within the scope of the invention as claimed.

I claim:

1. In a smoking set, a support, an ash tray pivotally carried thereby, a funnel-shaped member communicating with the interior of the ash tray and being rotatable with respect thereto, and a closure operatively connected to said member and normally closing the inner end thereof, said closure being swingable into open position when said member is rotated.

2. An ash tray comprising a receptacle, a tubular member communicating with said receptacle, a closure for the receptacle and being operatively connected to said member, said member when rotated in one direction opening the receptacle and when rotated in the opposite direction closing the receptacle.

3. An ash tray comprising a receptacle, a removable top therefor, said top having an opening, a closure for the opening pivotally carried by said top, a rotatable tubular member aligned with the opening and connected with the closure for opening and closing the closure when the tubular member is rotated.

4. In a smoking set, a support, an ash tray pivotally carried thereby, a funnel-shaped member communicating with the interior of the ash tray and being rotatable with respect thereto, a closure operatively connected to said member and normally closing the inner end thereof, said closure being swingable into

open position when said member is rotated, a cigarette holder carried by said member and being swingable into operative position when said member moves said closure into open position, and said ash tray is swung about its pivotal point on said support into its uppermost position.
